UNITED STATES PATENT OFFICE

GEORGE M. CLODFELTER, OF YONKERS, NEW YORK, ASSIGNOR TO THE RAIL JOINT COMPANY, OF NEW YORK, N. Y., A CORPORATION OF NEW YORK

TEMPORARY RAIL-JOINT SHIM

Application filed September 17, 1929. Serial No. 393,179.

As is well known, it is common practice in the art of railway track maintenance, when rails have become worn, to recondition them by supplying metal thereto to compensate for the loss of metal occasioned by wear.

While more or less wear occurs throughout the length of the head of a rail after extensive use, usually maximum wear occurs near the end of the rail, due to the pound of wheels

10 passing over the end of the rail to or from the end of an adjacent rail. It is, therefore, at and near the end of a worn rail, usually within the distance between the end of the rail and the adjacent end of the splice bar

15 commonly employed for joining the rail with an adjacent rail, that the need for supplying wear compensating metal to the head of the rail exists. According to general practice, this supply of wear compensating metal to

20 the head of a rail is effected by welding, as thereby the rail may expeditiously and economically be reconditioned without removing same from the track. Supplying wear compensating metal to a rail by welding, means of course, that the rail must be

25 heated, which manifestly results in weakening of the rail, so that in practice it has been found that, without support, when the rail end is heated during the process of welding, the head of the rail becomes mashed or

30 flattened if traffic passes over the rail before same has become sufficiently cool and hard following its reconditioning to withstand traffic. This is particularly true in connection with rail joints of the so-called "head-free" type because of the clearance existing

35 between the underside of the head of such a rail and the upper face of the joint bar employed therewith, the bar having loading engagement solely with the head fillet of the rail and leaving the side portions of the rail head unsupported.

Accordingly, the general purpose of the present invention is to provide simple, inexpensive, easily manipulated means for temporarily and reliably supporting the head of a rail, particularly a rail having joints of the so-called headfree type, against being mashed by traffic during and following the process of supplying wear compensating

metal thereto by welding, until the rail has sufficiently cooled to withstand traffic.

Preferably the present rail head supporting means consists of a wedge-shaped shim adapted temporarily to be placed between the underside of the rail head and the upper side of the joint bar, so as to fill the clearance space normally existing between the head of the bar and the underside of the rail head,

55 whereby the bar is adapted to receive traffic loads imposed on and transmitted through the rail head, thus to support the side portion of the rail head against downward movement. The said clearance space between the head of the bar and the underside of the head

50 of the rail increases in width from the head fillet towards the side of the rail, and since the shim is formed of wedge shape to fit this space, it follows that when load is im-

60 posed on the rail the tendency is to squeeze the shim outwardly from an operative position between the head of the joint bar and the underside of the rail head. Accordingly, it is a further purpose of the invention to so

65 form the shim that it may have interlocking engagement with the rail and joint bar for holding it against displacement from an operative position under the influence of traffic loads imposed on the rail.

70 With the foregoing and other purposes in view, the invention consists in the novel features of construction, combination and arrangement of parts as will be hereinafter more fully described, illustrated in the accompanying drawings and defined in the appended claims.

75 In the drawings, wherein like characters of reference denote corresponding parts in the different views:—

Figure 1 is a transverse sectional view 80 through a rail joint of the headfree type illustrating the present rail head supporting means operatively positioned between the head of the joint bar and the underside of the head of the rail; and

85 Figure 2 is a side elevation of the structure shown in Figure 1.

90 Referring to the drawings in detail, R, R, designate, generally, the meeting ends of a pair of rails and J, J, a pair of joint bars of

the so-called headfree type connecting said rails together.

As aforesaid, and as is well understood by those familiar with the rail joint art, a headfree rail joint is so designated because the joint bar J has loading engagement solely with the head fillet of the rail and head clearance from the underside of the rail head. With such a construction the head clearance space between the head of the bar and the underside of the head of the rail usually increases in width or depth from the head fillet of the rail outwardly towards the side of the rail, and therefore, outwardly of the head fillet of the rail, the rail head is unsupported and must of necessity be self-sustaining.

Also, as aforesaid, it is common practice, after a rail by long service has become appreciably worn at its end, as indicated at 8 in Fig. 2 of the drawings, to supply a body of wear compensating metal 9 to the head thereof by welding without removing the rail from the track, and this, of course, incurs heating of the rail with consequent weakening thereof, rendering the rail head quite susceptible of being mashed or distorted downwardly if traffic loads pass thereover before the operation of supplying wear compensating metal thereto has been completed, or before the rail has cooled following such operation.

According to the present invention, in order to overcome the foregoing disadvantage, a shim 10 of metal or other suitable material is provided, tapering in cross section from one side thereof to the other, so as effectively to fill the correspondingly shaped head clearance space between the head 12 of the joint bar J and the underside of the head 14 of the rail R. This shim is adapted to be placed in said space and to be retained therein in any suitable manner, prior to instituting welding of the wear compensating metal 9 upon the rail head, and to be removed following completion of the welding operation and after the rail has cooled. Said shim may be formed in a single length approximating the length of the joint bar, or it may be formed in two or more separate sections, two sections for example, one individual to each rail. In either event, to position the shim between the joint bar and the rail, all that is necessary is to loosen the usual joint bolts, slide the shim endwise between the joint bar and the rail to the position shown in the drawings, and then to tighten the joint bolts. When the welding operation is completed and the rail has cooled, removal of the shim may readily be effected by again loosening the joint bolts and sliding the shim from between the joint bar and the rail, after which the joint bolts may be tightened to restore the joint to its original condition. In this connection it will be understood, of course, that the wear com-

pensating metal 9 may be ground by an emery wheel or otherwise dressed to desired finished form either before or after removal of the shim 10. In its applied position said shim serves, as is manifest, as a filler for the space between the head of the joint bar and the underside of the head of the rail, so that during all of the time that said shim is operatively positioned between the joint bar and the rail, as shown in the drawings, any traffic imposed loads on the rail tending to mash or distort the head thereof downwardly are effectively resisted by the joint bar. Thus, by placing said shim between the joint bar and the rail prior to instituting the welding operation, and by allowing said shim to remain in such position until after the rail has cooled following the welding operation, traffic loads are rendered incapable of mashing or otherwise distorting the rail which is heat weakened during and immediately following the welding operation.

While any preferred means may be employed to hold the shim operatively positioned as shown between the joint bar and the rail, it is preferred, for purposes of simplicity and economy, to curve the inner, thin marginal portion of the shim downwardly as indicated at 16 so as to fit between the rounded inner corner 18 of the head of the joint bar and the head fillet 20 and the adjacent portion of the web 22 of the rail, thus to provide a retaining formation integral with the shim, which, by being clamped between the head of the joint bar and the head fillet and adjacent web portion of the rail, serves effectively to hold the shim operatively positioned between the joint bar and the rail against the influence of traffic loads on the rail tending to squeeze same outwardly due to its wedge shape.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. Means for temporarily supporting the head of a headfree rail during reconditioning of the rail head comprising a shim shaped to fit and to substantially fill the space between the underside of the rail head and the top of a related joint bar, and a tongue formation on said shim curved to fit between the head fillet of the rail and the upper inner corner of the joint bar to retain said shim in an operative position, the lower edge of said tongue terminating above the line of the joint bolts whereby the shim is insertible into and removable from the space between the rail

head and the joint bar without removing the joint bolts.

2. Means for temporarily supporting the head of a headfree rail during reconditioning of the rail head, comprising a shim shaped to fit and to substantially fill the space between the underside of the rail head and the top of a related joint bar, and means to retain said shim in an operative position, said shim being formed for insertion into and removal from the space between the rail head and the joint bar without removing the usual joint bolts.

In testimony whereof I hereunto affix my signature.

GEORGE M. CLODFELTER.
